UNITED STATES PATENT OFFICE.

SAMUEL V. SMITH, OF PHILADELPHIA, PENNSYLVANIA.

DESIGN FOR A FONT OF TYPE.

No. 39,889.

Specification for Design.

Patented March 23, 1909.

Application filed October 24, 1908. Serial No. 459,437. Term of patent 14 years.

To all whom it may concern:

Be it known that I, SAMUEL V. SMITH, a citizen of the United States, residing in Philadelphia, Pennsylvania, have invented a new, original, and ornamental Design for a Font of Type, of which the following is a specification, reference being had to the accompanying drawing, forming a part thereof, which shows the design of the font.

I claim:

The ornamental design for a font of type, as shown.

SAMUEL V. SMITH.
